FOOD CAFETERIA COUNTER

Murray A. Perl, New London, Frank Laspaluto, Waterford, and Robert J. Sevieri, Old Lyme, Conn., assignors to Facilities Design Associates, Inc., New London, Conn.

Filed Sept. 4, 1969, Ser. No. 19,005

Term of patent 14 years

Int. Cl. D6—01

U.S. Cl. D80—2

Fig. 1

Fig. 2

Fig. 3

Fig. 4

FIG. 1 is a top plan view of a food cafeteria counter showing our new design;

FIG. 2 is a side elevational view thereof;

FIG. 3 is a side elevational view thereof, showing the side opposite that seen in FIG. 2; and

FIG. 4 is an end elevational view thereof, the opposite end being the same as the end shown.

We claim:

The ornamental design for a food cafeteria counter, substantially as shown and described.
